Primary Examiner — Prabhakar Deshmukh(74) *Attorney, Agent, or Firm* — Memminger E. Wiggins(57) **CLAIM**

The ornamental design for a billiard bridge, as shown and described.

DESCRIPTION

FIG. 1 is a front perspective view of a billiard bridge showing my new design;

FIG. 2 is an another front perspective view thereof;

FIG. 3 is a left side elevational view thereof, the right side elevational view being a mirror image thereof;

FIG. 4 is a front elevational view thereof, the rear elevational view being a mirror image thereof;

FIG. 5 is a top plan view thereof;

FIG. 6 is a bottom plan view thereof; and,

FIG. 7 is a front perspective view thereof, shown in environmental use.

The broken lines indicate environment and forms no part of the claimed design.
